CLAIM

The ornamental design for a container with surface ornamentation, as shown and described.

DESCRIPTION

FIG. 1 is a front elevational view of the container with surface ornamentation of the present invention;

FIG. 2 is an additional front elevational view thereof, shown in an alternate unclaimed environment;

FIG. 3 is an additional front elevational view thereof, shown in an alternate unclaimed environment; and,

FIG. 4 is an additional front elevational view thereof, shown in an alternate unclaimed environment.

The broken line showing of the containers is included for the purpose of illustrating unclaimed environment and forms no part of the claimed design.

The claimed design is directed to the surface ornamentation shown in solid lines as applied to the curved surface of the containers shown in the drawing disclosure.
